Inventor:

T. G. Palmer

United States Patent Office.

T. G. PALMER, OF SHULTZVILLE, NEW YORK.

Letters Patent No. 83,995, dated November 10, 1868.

BRAKE FOR HORSE-POWER.

The Schedule referred to in these Letters Patent and making part of the same.

To all whom it may concern:

Be it known that I, T. G. PALMER, of Shultzville, in the county of Dutchess, and State of New York, have invented new and useful Improvements in Brakes for Horse-Power for threshing-machines and other like purposes; and I do hereby declare that the following is a full and complete description of the construction of the same, reference being had to the accompanying drawings, making a part of this specification, in which—

Figure 1 is a side view of a horse-power, with the driving-wheel, belt, and brake in position;

Figure 2 is a transverse section, showing the brake-lever resting upon the hinged support, which forms a part of the trigger; and

Figure 3 is a transverse view of the lever, after the trigger has been caused to fall, by the action of the belt, and the brake brought into action.

The horse-power is of the ordinary kind, having an endless belt provided with wooden lugs, and resting upon friction-wheels.

A represents the driving-wheel, and

B represents the belt, which passes around the pulley of the threshing-cylinder or other shaft to be driven. This belt may be open or crossed, as its action upon the trigger will be the same in either case, as will be fully shown.

C represents the lever of the brake, and

D represents the rubber which acts upon the driving-wheel A.

E represents a hinged support for the lever C of the brake. The inner end of this is hinged by a staple-bolt to the frame of the horse-power, in such a position that the belt, when thrown off from the pulley G of the threshing-cylinder, will pass a little above and in

front of it. The outer end of this support is formed into a hook, as shown at E, figs. 2 and 3.

F represents a trigger, which is secured to the frame, just below the bolt that secures the support E to the frame, the trigger being long enough, when extending horizontally, to reach beyond the belt, as shown in figs. 2 and 3. It is bent in the middle, as shown, and provided on the upper side of the obtuse angle with a sharp notch, into which the hooked end of the support E accurately fits. When the trigger is set, it has the position shown in figs. 1 and 2, the arm C of the brake resting with its weight upon the support E, the outer end of the trigger F being horizontal a little distance below the belt B, as shown in fig. 2. Now, while in this position, if the belt, from any cause, be slipped from the pulley, it would fall upon the trigger, and move it forward in the direction of the running of the belt, and in doing so would release the support E, bringing the parts E F C into the respective positions shown in fig. 3, and thus bring the rubber D into firm contact with the periphery of the driving-wheel A, and by this means put a stop to the motion of the horse-power.

It is obvious that the belt can run in either direction, either open or crossed, and the same results would follow.

What I claim as my improvement, and desire to secure by Letters Patent, is—

The herein-described brake-combination, consisting of the lever C, rubber D, support E, and trigger F, or their equivalents, all constructed and arranged as and for the purpose specified.
